(73) Assignee: **Mazda Motor Corporation**, Hiroshima (JP)

(57) **CLAIM**

The ornamental design for a bumper of motor vehicle, as shown and described.

(**) Term: **14 Years**

DESCRIPTION

The patent or application file contains at least one drawing executed in color. Copies of this patent or patent application publication with color drawings will be provided by the Office upon request and payment of the necessary fee.

FIG. 1 is a front perspective view of a bumper of motor vehicle;

FIG. 2 is a front view thereof;

FIG. 3 is a left side view thereof, the opposite side being a mirror image of the side shown herein;

FIG. 4 is a top view thereof; and,

FIG. 5 is a bottom view thereof.

The broken lines shown in FIGS. 1, 4, and 5 are for illustrative purpose only and form no part of the claimed design.
